UNITED STATES PATENT OFFICE.

WILLIAM J. BOHAN, OF ST. PAUL, MINNESOTA.

LOCOMOTIVE.

1,242,762.

Specification of Letters Patent.

Patented Oct. 9, 1917.

Application filed April 3, 1916. Serial No. 88,518.

To all whom it may concern:

Be it known that I, WILLIAM J. BOHAN, a citizen of the United States, residing at St. Paul, in the county of Ramsey and State 5 of Minnesota, have invented certain new and useful Improvements in Locomotives; and I do hereby declare the following to be a full, clear, and exact description of the invention, such as will enable others 10 skilled in the art to which it appertains to make and use the same.

My present invention relates to locomotives and is in the nature of an improvement on or modification of the locomotive 15 disclosed and broadly claimed in my pending application S. No. 50,834, filed of date, September 15, 1915, and entitled "Locomotive."

The present locomotive and the locomotive of my said prior application employ 20 auxiliary motor trucks operated by a generator or dynamo driven by a steam motor or turbine, which latter, under certain conditions, is driven entirely by the exhaust 25 from the cylinders of the reciprocating engines, under certain conditions is driven by live steam, and under certain conditions is driven by mixed live and exhaust steam. The present invention, as one of its major 30 features, involves an improvement over the prior application, in the means for controlling the supply of live steam to the steam motor or turbine of the "turbo-generator set."

35 The present invention also involves a novel arrangement of a plurality of engine tenders with condensers, cooling tower and circulating connections. The invention further involves certain other minor 40 but important features, all of which will be hereinafter described and defined in the claims.

In the accompanying drawings which illustrate the invention, like characters indicate like parts throughout the several 45 views.

Referring to the drawings:

Figures 1 and 2 are supplemental views in side elevation with some parts broken 50 away, some parts removed and some parts indicated in diagram only, and illustrating the improved locomotive including two connected tenders. This locomotive is designated as a "turbo-electric compound locomotive."

Of the parts of the locomotive proper,

the numeral 1 indicates the boiler, the numeral 2 the cab, the numeral 3 the cylinders, the numeral 4 the main drive wheels, the numeral 6 the feed water pump, the numeral 7 the main steam pipe from boiler to cylinders, and the numerals 8, 9 and 9^a, respectively, the frame, the front wheels and axles of the front truck which carries a very considerable part of the weight of the 60 front part of the locomotive boiler. The truck frame 8 carries electric motors 10 that are geared to the axles 9 of the said front truck. As shown, the truck frame 8 is connected to the saddle of the cylinders 3, by articulate joints 11. The said front truck is, as shown, provided with front or pilot wheels 12 diagrammatically indicated in Fig. 1. The front portion of this said truck carries a "turbo-generator set" made up of 65 an electric generator or dynamo 13 and a steam turbine 14, the latter being connected to drive the former, and both being of any suitable well known construction. For instance, the said steam turbine 14 may be 70 of the type known as a low pressure or exhaust steam turbine. The numeral 15 indicates a two-branch exhaust pipe which leads from the locomotive cylinders 3, is equipped in its branches with check valves 75 15^a, and is connected to a receiver tank 16, which latter, in turn, is connected by a pipe 17 to the turbine 14.

In this improved locomotive, the usual exhaust nozzle is dispensed with and a so-called exhaust by-pass pipe 18 is extended to the atmosphere, and leads from the receiver. In this exhaust by-pass 18, is an over-pressure valve 19 of standard or any suitable type, which is set to open and permits exhaust through the said by-pass under a predetermined pressure, which we may, for illustration, assume to be ten pounds.

The exhaust port of the steam turbine 14 is connected, by a large exhaust pipe 20, to 100 a main condenser which, in practice, is preferably carried on the locomotive tender, presently to be described.

As a feature of the present invention, I interpose an auxiliary condenser 21 in the 105 exhaust pipe 20 and carry the same on the locomotive, preferably at the top of the boiler, so as to provide drainage rearwardly to the main condenser on the tender.

For the supply of live steam from the 110 boiler to the turbine 14, a pipe 22 is extended from the boiler head, directly to

the receiver 16 and from thence, to the turbine, through the pipe 17, check valve 15^a, as is obvious, cutting off live steam to the engine cylinders from this source. The live steam pipe 22 is provided with a control valve 22^a preferably located within the cab 2.

As a very important feature of this invention, a pressure reducing valve 23 is interposed in the steam pipe 22. This pressure reducing valve may be of any well known or suitable construction arranged to maintain a predetermined pressure in the receiver 16 of, for illustration, five pounds, but in any case, set to maintain a pressure less than that required to open the over-pressure valve 19. As a feature of this invention, the engine is provided with a plurality of tenders, and the truck wheels thereof are driven by electric motors. From a broad point of view, these tenders constitute motor driven tender units or cars, but in their more specific function as tenders, they are brought into a novel combination with the locomotive proper, all as will presently appear. The tenders are equipped with the usual water tanks and their body portions are indicated by the numerals 24 and 25. The truck wheels 26 are driven by electric motors 27 suitably supported on the truck frames and suitably geared to the axles of the said truck wheels.

In the preferred arrangement, the tender body 25 is equipped with a condenser 28 of any suitable construction, but as shown, of tubular type, and the same tender carries a cooling tower 29. The tanks of the two tenders are connected by an equalizing pipe 30 having a suitable flexible portion. The delivery end of the exhaust pipe 20 has a flexible joint 31 between the locomotive and first tender, and the rear end thereof is connected directly or indirectly to the tubular part of the condenser 28, while the other extremity, to ~~z~~, the lower extremity of said tubular part of the condenser, is connected by a suction pipe 32 to a vacuum pump 33 of suitable construction, and which, in turn, discharges to the cooling tower 29 through a pipe 34. On the rear tender is a pump 35, preferably of the rotary type, having a suction pipe 36 leading from the lower portion of the tank of the rear tender. This pump 35 is provided with a discharge pipe 37 that is connected, through a flexible section 38 to the bottom of the water compartment of the condenser 28. The upper portion of the water compartment of said condenser has a discharge pipe 39 that delivers the cooling water also to the cooling tower 29.

The several above described electric motors 10 and 27 are all supplied with current from the generator 13. Any suitable system of wiring may be employed for this purpose, but for simplicity of illustration,

the said motors are shown as connected, in parallel, by wires 40 and 41 that tap leads 42 and 43 from the said generator. In practice, however, I would advisably use a system of electric supply and control, such as illustrated in a general way, in my said prior application.

Operation.

Steam is, of course, supplied to the cylinders 3 of the locomotive in the usual way, through the throttle valve and the main steam supply pipe 7. In starting the locomotive, the turbine 14 should be started either simultaneously with, or a little ahead of the admission of live steam to the cylinders 3. This, as is evident, may be accomplished by opening the controlling valve 22^a. In this starting action, and in fact, at all times, the check valve 15^a prevents the steam from flowing back into the steam chests of the steam cylinders, but will open to permit exhaust therefrom into the receiver 16.

As the over-producing valve 19 is set to open under higher pressure than the reducing valve 23, there is no possibility of the waste of live steam to the atmosphere, through the by-pass 18. With the reducing valve 23 set, as assumed, for five pounds pressure, five pounds will be the maximum pressure obtainable, from the live steam source, within the receiver 16, but the exhaust from the engine cylinders, under certain conditions, will raise the pressure in the receiver sometimes to a point in excess of the assumed pressure of ten pounds, at which the over-pressure valve 19 is set to open, and in that event, the surplus steam will be exhausted through the by-pass 18. This will happen only when the turbine is not taking steam as fast as supplied from the exhaust. Otherwise stated, at any time when the pressure in the receiver 16 exceeds the assumed pressure of five pounds, the turbine will be using only exhaust steam. The only time that it is really necessary to close the valve 22^a is when it is desired to stop the turbine while the engine is standing still or not working. Nevertheless, if the valve 22 be closed while the engine is running, then only exhaust steam will be available for operating the turbine.

The pressure reducing valve in the steam supply pipe to the steam motor or turbine is a very highly important feature, because it controls the pressure of live steam in the receiver and keeps the same below a pressure which might otherwise create excessive back pressure against the exhaust from the engine cylinders.

When the locomotive is operating at slow speeds and long cut-off, the supply of steam taken from the locomotive boiler is essentially very small, and only a very small pro-

portion of the maximum supply which the boiler is capable of generating and furnishing. By the use of the reducing valve in the supply pipe 22, a constant maximum supply 5 of steam can be maintained in the receiver 16. In other words, the steam supply from the pipe 22 will act as a "booster" to the exhaust steam supply from the cylinders 3 when operating at slow speeds. When the 10 locomotive has reached its maximum speed, or the speed where the locomotive cylinders 3 most nearly approach using all of the live steam supply from the locomotive boiler, the supply of live steam in pipe 22 will be automatically controlled in the receiver 16, due 15 to the fact that the supply of exhaust steam from the cylinders 3, at the speed at which they use practically all of the boiler supply, will build up a pressure in the receiver 16 sufficient to automatically check the volume 20 of live steam in pipe 22. Furthermore, it will be noted that the entire charge in the receiver 16 is dependent upon the load capacity imposed upon the turbine, and consequently, upon the quantity of steam required 25 to operate the turbine. If all of the steam supplied in receiver 16 is in excess of what is required to operate the turbine, pressure will build up in said receiver and at the predetermined point, assumed to be ten pounds, blow-off to atmosphere. This combination enables the locomotive to be operated either by the turbine unit or by the reciprocating unit or both. In event of either 30 of the power units failing, as in case of a break-down, the available unit can be used to draw a train into a terminal station or siding.

A highly important feature, however, is 40 found in the fact that this system enables the combined engine to operate at a maximum boiler capacity of the locomotive, at all times, and renders available several times the tractive power ordinarily obtained from the 45 same locomotive boiler operating in the usual manner. Substantially the whole weight of the locomotive and, in fact, of a train, may be utilized for traction.

It is further important to note that the 50 pump 33 will produce a suction or piston vacuum in the exhaust pipe 20. The auxiliary condenser 21 not only relieves the main condenser 28 and increases the suction or vacuum produced by condensation, but does 55 this at a point close to the turbine.

By applying the condenser and tower on the one tender and the pump on the other, the coldest water is always available for cooling the condenser. Moreover, the two connected tanks of the two tenders give a large 60 water supply for condensing purposes and for supplying the locomotive, making it particularly advantageous in places where bad water prevails and the supply of good water 65 is scarce.

What I claim is:

1. In a locomotive having a plurality of traction wheels, the combination with a steam cylinder and driving connections between said cylinder and some of said wheels, 70 of means for supplying live steam from the boiler to said cylinder, a steam-operated motor, driving means between said motor and others of said wheels, a steam receiver, an inlet thereto for the exhaust steam from said cylinder, an inlet thereto for live steam, an exit therefrom for supplying steam to operate said motor, and means for preventing the pressure from said live steam supplied to the receiver overcoming the pressure of the exhaust steam from said cylinder. 75

2. In a locomotive having a plurality of traction wheels, the combination with a steam cylinder and driving connections between said cylinder and some of said wheels, 80 said cylinder being supplied by live steam from the locomotive boiler, of electric motor drives for others of said wheels, a turbo-generator set for supplying current to said motors, a steam receiver, connections between 85 said receiver and said cylinder for transferring the exhaust from the cylinder to said receiver, a live steam supply for said receiver, a connection from said receiver to the turbo-generator set for operating the latter, 90 and means for preventing the pressure from the live steam supplied to the receiver overcoming the pressure of the exhaust steam from the cylinder. 95

3. In a locomotive having a plurality of traction wheels, the combination with steam cylinders and connections from said cylinders to some of said wheels for driving the latter, electric motor drives for others of said wheels, a turbo-generator set for supplying 100 current to said motors, a steam receiver interposed between said cylinders and the turbine and adapted to receive the exhaust steam from the cylinders and transfer the same to the turbine, a check valve in the connections between the cylinders and said receiver, a pipe for supplying live steam to said receiver and having a reducing valve 105 therein, and a by-pass pipe leading from said receiver and having an over-pressure valve 110 therein, substantially as and for the purposes specified. 115

4. In a locomotive, the combination with the boiler steam cylinders, drive wheels, and connections between the same, of a truck associated with said locomotive, an electric motor for driving the wheels of said truck, an electric generator supplying current to said motor, a steam motor for driving said generator, and steam connections including 120 a reduction valve supplying steam from said boiler to said steam motor. 125

5. In a locomotive, the combination with the steam cylinders, driving wheels and connections between the same, of a truck con- 130

- connected to said locomotive, an electric motor for driving the wheels of said truck, an electric generator, supplying current to said motor, a steam motor for driving said generator, a receiver connected to said steam turbine and to the exhaust from the cylinders of said locomotive, and steam connections, including a pressure reducing valve, supplying steam from the locomotive boiler to said receiver.
6. In a locomotive, the combination with the steam cylinders, driving wheels and connections between the same, of a truck connected to said locomotive, an electric motor for driving the wheels of said truck, an electric generator supplying current to said motor, a steam motor for driving said generator, a receiver connected to said steam turbine and to the exhaust from the cylinders of said locomotive, and steam connections, including a pressure reducing valve, supplying steam from the locomotive boiler to said receiver, the connections between said receiver and exhaust to the said cylinders including a check valve preventing a flow of steam from said receiver to said cylinders.
7. In a locomotive, the combination with the steam cylinders, driving wheels and connections between the same, of a truck connected to said locomotive, an electric motor for driving the wheels of said truck, an electric generator supplying current to said motor, a steam motor for driving said generator, a receiver connected to said steam turbine and to the exhaust from the cylinders of said locomotive, and steam connections, including a pressure reducing valve, supplying steam from the locomotive boiler to said receiver, and a by-pass leading from said receiver and equipped with an over-pressure valve set to open under a pressure greater than that required to open said reducing valve.
8. In a locomotive, the combination with the steam cylinders, driving wheels and connections between the same, of a truck connected to said locomotive, an electric motor for driving the wheels of said truck, an electric generator supplying current to said motor, a steam motor for driving said generator, a receiver connected to said steam turbine and to the exhaust from the cylinders of said locomotive, and steam connections, including a pressure reducing valve, supplying steam from the locomotive boiler to said receiver, the connections between said receiver and exhaust to the said cylinders including a check valve preventing a flow of steam from said receiver to said cylinders,
- and a by-pass leading from said receiver and equipped with an over-pressure valve set to open under a pressure greater than that required to open said reducing valve.
9. In a locomotive, the combination with steam cylinders, drive wheels and driving connections between the same, of a truck connected to said locomotive, a motor for driving the wheels of said truck, an electric generator supplying said electric motor, a steam motor for driving said generator, and means whereby live steam from the boiler or exhaust from the engine cylinders, or both, may be employed to drive said steam motor.
10. The combination with the steam cylinders, drive wheels and driving connections of a locomotive proper, of a multiplicity of cars connected to said locomotive, electric motors for driving the wheels of said cars, an electric generator on said locomotive for supplying current to the motors of the several cars, a steam motor for driving said generator, and steam connections from the locomotive boiler to said steam turbine.
11. The combination with the steam cylinders, drive wheels and driving connections of a locomotive proper, of a multiplicity of cars connected to said locomotive, electric motors for driving the wheels of said cars, an electric generator supplying current to the motors of the several cars, a steam motor for driving said generator, and live steam and exhaust steam connections from the locomotive boiler and cylinders to said steam motor.
12. The combination with the steam cylinders, drive wheels and driving connections of a locomotive proper, of a plurality of tenders connected thereto, motors for driving the wheels of said tenders, an electric generator supplying said motors, a steam motor for driving said generator, steam connections for driving said steam motor from said boiler, a condenser on one of said tenders, an exhaust pipe from the exhaust of said steam motor to said condenser, a pump on the other tender provided with circulating connections for delivering water from the tank on which it is applied to the condenser on the other tank, and a water equalizing connection between the tanks of said two tenders.

In testimony whereof I affix my signature in presence of two witnesses.

WILLIAM J. BOHAN.
